UNITED STATES PATENT OFFICE.

GRANVILLE E. LUNTSFORD, OF CORNING, ARKANSAS.

TRAIN-ORDER-DELIVERY MECHANISM.

1,333,723.

Specification of Letters Patent. Patented Mar. 16, 1920.

Application filed June 30, 1919. Serial No. 307,568.

To all whom it may concern:

Be it known that I, GRANVILLE E. LUNTSFORD, a citizen of the United States, residing at Corning, in the county of Clay and State 5 of Arkansas, have invented certain new and useful Improvements in Train-Order-Delivery Mechanisms, of which the following is a specification, reference being had to the accompanying drawings.

10 This invention relates to devices for delivering written train orders to passing trains at stations, and particularly to that class of devices of this character wherein the train orders are held on a hoop, as it 15 may be termed, so supported that the engineer, fireman, conductor, or other trainman may seize the hoop or pass his arm through the hoop as the train passes the station and thus secure the order without stopping the 20 train.

At the present time practically every road in the country has the same system of delivering train orders, that is the station agent or employee stands beside the track 25 and holds in his hand a hoop of wood having a handle and having mounted thereon a spring clasp in which the message or train order is disposed. The trainman, as for instance, the engineer, fireman, conductor or 30 train hand on the rear end of the train, projects his arm and as the train passes, thrusts his arm through the hoop and thus secures the order. Sometimes the trainman will miss the hoop, particularly at night, and 35 it is obvious that in order to secure any certainty, it is necessary that the person delivering the order should stand at all times in a certain place with the hoop disposed in a certain position. Not so much difficulty is 40 experienced during the day, but at night it is particularly necessary that the engineer or conductor on the train should know precisely where the hoop is in order that it may be grasped or taken off. Where trains are 45 running at a high speed, it is manifestly dangerous, particularly at night, for an employee to stand a short distance from the track while the train is passing and hold out this hoop, and often employees have been 50 injured, struck or run over by handing out these orders. As a consequence, many employees lack the nerve to properly deliver these orders, and this is particularly true of more or less ignorant employees. Furthermore, where the train is a double header, 55 that is is being pulled by two engines, it is

necessary to deliver four orders to the train, one to each engineer, one to the conductor of the train, and one to the brakeman at the extreme rear end of the train, and if the 60 train is proceeding at a high rate of speed, and particularly if it be night, it is somewhat difficult to deliver all four of these orders.

A further object is to provide a mechanism of this character whereby anywhere from one to four orders may be supported and whereby when more than one order is to be delivered, the hoops supporting the orders will be presented in serial order, it 70 being manifest that it is a necessity of a mechanism of this kind that only one hoop shall be supported in delivering position at any one time, and that then another order shall be automatically shifted into deliver- 75 ing position.

And a further object is to provide a mechanism of this character in which after the orders are placed on their proper hoops and the hoops set in their proper position 80 on the mechanism, one of the arms supporting the corresponding hoop will be turned down into its delivering position, and that thereafter when this first hoop is taken off, the other hoops will successively fall into 85 their delivering positions, and in this connection to provide a mechanism so constructed that it does not matter which of the arms supporting the hoops is disposed in its delivering position, thus making the de- 90 vice fool-proof to the extent that even an ignorant and inattentive employee may properly set the device.

A further object is to provide a device of 95 this character which is very simple in construction, which is easily operated, which is easily set, and which may be adjusted so as to support the hoops at that angle best suited to the passing trains, and further to provide a device of this character whereon 100 lanterns may be supported at night so as to indicate to the engineer, conductor, etc., the precise position of the hoop carrying the message or order.

Other objects will appear in the course 105 of the following description.

My invention is illustrated in the accompanying drawings, wherein:

Figure 1 is a side elevation of a train order delivery mechanism constructed in accordance with my invention;

Fig. 2 is fragmentary vertical sectional

view, showing the position of the parts when one of the train order holders is detached and its corresponding arm is swinging to its dropped position;

5 Fig. 3 is a fragmentary perspective view of the upper end of the brace 14;

Fig. 4 is a section on line 4—4 of Fig. 5, showing the position of the parts taken when one of the arms is swung to its 10 dropped position and the next adjacent arm is moving to a horizontal position;

Fig. 5 is a front elevation of the construction shown in Fig. 4.

Referring to these drawings, it will be 15 seen that the supporting frame of the mechanism consists of a U-shaped yoke bar 10, which is mounted in any suitable manner upon a post 11, which may be of any desired height. Attached to the upwardly extending arms of the U-shaped frame is a 20 forwardly projecting U-shaped member 12 which, at its rear end, is supported by bolts 13 and which, at its forward end, is supported by braces 14, these braces being more 25 or less angular in form and being bolted to the forward end of the U-shaped member 12 and preferably extending up above this member and being formed at their upper ends with sockets 15 for the reception of 30 the bail or handle of a lantern. The rear ends of these braces are longitudinally slotted, as at 16, and a bolt 17 passes through these slots. This bolt also supports an upwardly extending, U-shaped rest 18 35 which extends upward beyond the upper ends of the arms of the supporting frame 10, and has a cross bar 19.

Passing through the upper ends of the arms of the frame 10 is a shaft 20 which 40 projects beyond these arms and is provided with collars 21 holding it from longitudinal movement but permitting its rotation. This shaft carries upon one end a hand wheel 22 or other means whereby the shaft may be 45 rotated.

Loosely mounted upon the shaft between the arms of the U-shaped frame 10 are a plurality of freely swinging arms 23, all of these arms being alike in construction. 50 These arms 23 are spaced from each other by washers 24 so that one arm may swing freely independently of any other arm. These arms in their normal position all extend upward and rearward and rest against the cross bar 19. Also mounted upon the shaft to rotate therewith, however, are two collars 25 disposed inward of the arms of the frame 10, these collars having outwardly extending bars 26 connected by a cross bar 27.

Each of the swinging arms 23 consists of a metallic bar of any desired cross section, area and length, and it will be noted that the shaft 20 passes through these arms below the middle thereof so that the arms are 65

unequally pivoted. I have shown four of these arms mounted upon the shaft and have indicated the arms by the letters A, B, C and D. The arms A, B, and C are each formed intermediate the shaft, and one 70 extremity of the arm preferably with a transverse recess 28. The arm D, however, is not provided with this recess, but is provided with a pin 29 which projects into the recess of the arm C, and the arm C is 75 provided with a pin 29 projecting into the recess of the arm B. The arm B is provided with a pin projecting into the arm A. It will be, therefore, seen that three of the arms are provided with the pins 29. These 80 pins constitute stop lugs, as will hereafter appear. The free ends of the arms, that is the normally upper ends, are provided upon their rear faces with flat leaf springs 30 which, at their lower ends, are spaced 85 from the arms by means of spacers 31. Bolts 32 pass through these arms of the corresponding springs. These springs 30, in conjunction with the upper ends of the arms, form sockets for the reception of the 90 shanks of the message or order-carrying hoops 33.

One of these hoops is shown in detail in Fig. 1. The hoops are made of wood and ordinarily have a diameter of about a foot 95 and a half more or less, and formed to provide a tangentially extending shank 34. This shank is tapered at its end so that it may be wedged down into position between the spring 30 and the corresponding arm, and under these circumstances the hoop will extend transversely to the track. At the junction of the shank and hoop, or at any other desired place, there is disposed a spring clamp 35 which may be of any suitable form, and the order is folded and disposed in this spring clamp. I do not wish to be limited to the particular construction of the hoops, nor to the means whereby the order is held thereon. The shanks of the 100 hoops are disposed within the sockets, as 105 previously described, so that the hoops may be withdrawn by simply inserting the arm through the hoops, whereupon the hoops will swing laterally in the sockets and pull out 110 therefrom with relative ease.

The operation of this mechanism is as follows: Assuming that an ordinary train is about to pass and duplicate orders are to be delivered to the engineer and the conductor of the train, then these duplicate orders are attached to the respective hoops 33 and the shanks or handles of the hoops inserted in any two of the arms A, B, C and D. One of the arms containing an order is 115 now turned down to an approximately horizontal position, that is to the position shown in Fig. 1, with the shank 34 of the hoop resting upon the cross bar of the U-shaped support 12. This hoop with its order attached 120

thereto is now in position where it may be taken off by the engineer or fireman on the locomotive of the train. As soon as the order is taken off, this arm, which I will assume is the arm D, is released and falls from its approximately horizontal position to a depending position, and as it rotates, the stud or pin 29 will strike that portion of the arm C below the pivot and turn this 5 arm to a horizontal position. If this arm supports a hoop, the arm will be stopped when the shank of the hoop strikes on the cross bar of the support 12. If it does not support a hoop, the arm will continue to 10 swing down until its pin 29 strikes the lower portion of the arm B, when this will swing down. If this arm does not support a hoop, it will continue to swing until its pin 29 strikes the lower portion of the arm A, 15 when this arm, which I will assume supports the second hoop, will swing to an approximately horizontal position with the shank of the hoop resting on the cross bar of the support 12. Then when this hoop has 20 been taken off, the arm will swing downward to its depending position. All of these arms will now have been swung down to a depending position and they may be turned upward to a position supported against the 25 cross bar 19 by simply rotating the shaft 30 through the hand wheel 22.

Now I have considered in the above description that the arm D has been initially swung to its approximately horizontal position and that thereafter the arms C, B and A will successively be released, but it does not matter whether the arm D is first disposed in its horizontal position, or the arm A is disposed in this position, exactly the 35 same result will occur. If the arm A be the one which is initially disposed in its horizontal position, then when this is released by the taking off of the order-carrying hoop, the arm will swing downward until that 40 portion of it normally below the pivot shaft 20 will strike the pin 29 of the arm and rotate this arm, and this, after it has swung below the horizontal position, will strike the pin of the arm C and will swing it over, and 45 this in turn will swing the arm D over. Thus, it does not matter which of the arms the attendant disposes in a horizontal position. The arm C might be the one disposed in a horizontal position. In this case, both 50 the arms D and B would be rotated, it is true, but as one or both of these arms will not contain any message, no harm can be done and they would simply swing to their lowered positions and bring the arm A into 55 60 position to deliver the message.

Where four train orders are to be delivered, as to a "double header" train, four hoops will be used, and either one of the end arm A or D will be initially turned down to 65 its horizontal position. Thereafter, the op-

eration is precisely the same as heretofore described. As fast as one hoop has been removed, another hoop will drop to its delivering position.

By this mechanism it will be seen that 70 only one hoop at a time can be presented, and that these order-carrying hoops will be presented one after another until they are all taken off. The fact that either of the end arms may be the arm initially shifted 75 to its horizontal position with a message therein, is of particular importance in localities where labor is more or less ignorant and unskilled and where the employee arranging the arms might not take care that 80 one particular arm was disposed in a horizontal position, and that is why I have so constructed the mechanism that the arms will be operated successively beginning at either end.

It is to be noted that the supports or rests 85 18 and 19 may be adjusted so as to increase or decrease the angle of the arms A, B, C and D when they are disposed in their operative positions so that while the arms will 90 not swing accidentally to a discharge position, yet at the same time they may be readily tipped from their static position without the expenditure of much force. Likewise, the U-shaped supporting yoke 12 95 100 may be adjusted so as to raise or lower the cross bar thereof within certain limits to thereby support the arms at a greater or less angle when they are in their delivering position and vertically adjust the position of 105 the message-carrying hoops as a consequence. At night, lanterns or other suitable illuminated signals are to be hung on the hooks 15 so as to indicate the position of the hoops and illuminate these hoops sufficiently 110 so that a trainman can readily pass his arm through the hoop. Of course, other devices, somewhat like mail bag catchers, might be provided for the purpose of removing these hoops if desired, but obviously this forms no 115 part of my invention.

While I have illustrated four arms A, B, C and D, yet it is obvious that less than four arms might be used on sections of road where trains are not double headed, or that 115 more arms might be used than four. Thus, for instance, the duplicate orders for one train might be placed on two arms and duplicate orders for a next succeeding train placed on the other two arms, and then 120 orders might be arranged thus on a plurality of arms for a plurality of successive trains. Under ordinary circumstances, however, four arms 23 will be all that is necessary.

While I have illustrated a form of my invention which I have found to be thoroughly effective and which is very simple, yet it is obvious that various details might be changed and that the parts might be rearranged without departing from the spirit of 125 130

the invention. Furthermore, it will be, of course, obvious that the dimensions of the mechanism will be changed according to the height of locomotives and cars, or the regulations of the road.

5 I claim:

1. A train order delivery mechanism including two train order supporting members each independently shiftable from a retracted to a delivery position, means for supporting one of the members in a delivery position and the other in its retracted position, and means actuated automatically upon the removal of the order carried by the first 10 named member causing the second named member to be projected to its delivery position.

2. A train order delivery mechanism including a plurality of independently pivoted train order supporting arms each independently shiftable from a retracted to a projected position, means for supporting any one of the arms in a delivery position, means for supporting any one of the arms 20 in a retracted position, and means actuated automatically upon the removal of an order carried by any arm in its projected position causing the next successive arm in either direction to be shifted to its delivery position.

3. A train order delivery mechanism including a series of train order supporting members each provided with means for supporting a train order carrying hoop and 35 each mounted for independent movement from a retracted to a projected delivery position and being supported in its delivery position by the hoop attached thereto, and means actuated upon the movement of any 40 one arm past its delivery position causing a serially successive arm to be projected to a delivery position.

4. A train order delivery mechanism including a supporting shaft, a support disposed in a horizontal plane in advance of said shaft, a support disposed rearward and above the shaft, a plurality of train order carrying arms pivotally mounted upon the shaft for independent movement, 45 each arm having at one end means for detachably supporting an order carrying hoop, the arms having a length from their pivotal axis to the hoop supporting ends less than the distance between said shaft and the first 50 named support, each of said arms being formed at its extremity with a laterally open socket, order supporting hoops having shanks insertible into said sockets and adapted to rest upon the first named support 55 when the corresponding arm is in its projected position, and means carried by each arm engaging with the next successive arm 60 when the train order hoop has been removed and the first named arm dropped to a depending position and acting to rotate the 65

next successive arm from its raised and retracted position to a horizontal position.

5. A train order delivery mechanism including a plurality of independently pivoted arms, each having a laterally open 70 socket at its end, a vertically adjustable horizontal support, train order carrying members, each having a handle insertible into the socket of the corresponding arm and adapted to rest upon said support when the 75 arms are in a substantially horizontal position and when withdrawn from the arms permitting the arms to swing to a vertical depending position, and means on each arm acting upon the swinging of any one arm 80 to a vertical depending position automatically engaging a serially successive arm to cause said last named arm to swing to a horizontal position.

6. A train order delivery mechanism including a supporting shaft, a stop disposed in a horizontal plane in advance of said shaft, a plurality of train order carrying arms pivotally mounted upon the shaft for independent movement from a position approximately at right angles to the plane of said support to a position parallel to the plane of the support, each of said arms having a socket at its extremity, train-order carrying members, each having a shank insertible into the socket of the arm, the arms having a length less than the distance between the pivotal axis and said support whereby the train-order carrying member on an arm will support it against said stop, 100 and means carried upon each arm acting upon a withdrawal of a train-order carrying member and the movement of the arm thereof from its position in a plane with said stop engaging a serially successive arm 105 to cause it to rotate into the same plane as the stop.

7. A train order delivery mechanism including a supporting shaft, a support disposed in an approximately horizontal plane 110 in advance of said shaft, a support disposed rearward and above the shaft, a plurality of train order carrying arms pivotally mounted upon the shaft for independent movement, each arm having at one end means for detachably supporting an order carrying hoop, the arms having a length from their pivotal axis to the hoop supporting ends less than the distance between said shaft and the first named support, order supporting hoops having shanks engageable 115 with said arms and adapted to engage said first named support when the corresponding arm is turned into an approximately horizontal position, each arm having a projecting portion which, when the arm is rotated from its approximately horizontal position to a depending position consequent upon the removal of an order carrying member, will engage the serially successive arm 120 125 130

and rotate it from a position against the second named support to an approximately horizontal position.

8. A train order delivery mechanism including a shaft, a support disposed horizontally in advance of said shaft, a support disposed rearward and above the shaft, and an arm pivoted upon said shaft, the arm at one end having a spring clip extending parallel to the arm but disposed in spaced relation to one face thereof, the distance between the pivotal axis of the arm and the extremity of the last named end of the arm being less than the distance between the pivotal axis and the first named support, and a train order carrying member having a wedge-shaped shank insertible between the spring clip and the face of the arm and when so inserted adapted to rest upon the first named support and support the arm in an approximately horizontal position.

9. A train order delivery mechanism including a supporting shaft, a support disposed in an approximately horizontal plane in advance of said shaft, a plurality of arms pivotally mounted upon the shaft, each arm extending beyond the shaft on each side, one end portion of the arm being longer than the other and the longer end of the arm being provided at its extremity with means for detachably engaging a train order carrying member, the distance between the axis of each arm and the last named end of the arm being less than the distance between said axis and the support, all but one of the arms being formed with recesses in their side faces and all but one of the arms being provided with pins projecting laterally from the arm and into the corresponding recess of a next adjacent arm, whereby a rotation of one of the arms to a predetermined angular extent will cause the pin of said arm to engage a portion of the next adjacent arm to cause the rotation of the next adjacent arm, and train order carrying members having shanks for engagement by said means on the extremity of the arms, said train order members being adapted to rest upon the first named support when the arms are turned into a horizontal position, and a support with which the arms engage and by which they are supported in an approximately vertical and retracted position.

10. A train order delivery mechanism including a plurality of independently pivoted arms, each formed at one end with means for engaging a train order carrying member, means for supporting said arms in an upwardly and rearwardly inclined position but permitting the arms to swing to a depending position, means for supporting any one of said arms in an approximately horizontal position when the corresponding train order will be projected, and means act-

ing upon the removal of a train order member from the last named arm causing a serially successive arm in either direction to swing downward from its upwardly and rearwardly inclined position.

11. A train order delivery mechanism including a plurality of pivoted arms, each formed at one end with means for engaging a train order carrying member, means for supporting said arms in an upwardly and rearwardly inclined position but permitting the arms to swing to a depending position, means for supporting any one of said arms in an approximately horizontal position with the corresponding train order projected, and means acting upon the removal of a train order member from the last named arm causing a serially successive arm to swing downward from its upwardly and rearwardly inclined position, and manually actuatable means for resetting all of said arms from a depending position to an upwardly and rearwardly inclined position.

12. A train order delivery mechanism including a frame, a supporting shaft mounted thereon, a horizontally disposed support mounted on the frame in advance of the shaft, a horizontally disposed support mounted on the frame above and rearward of the shaft, a plurality of arms unequally pivoted upon the shaft for movement in a vertical plane past said first named supporting means, said arms being adapted to be disposed in an upwardly and rearwardly inclined position against the second named supporting means, the shaft being independently rotatable with relation to the arms and carrying an elongated link thereon engageable with the arms to rotate them unitarily, the shaft having means whereby it may be manually rotated, each of said arms having at one end means for detachable engagement with a train order carrying member, the distance between the axis of the arm and this end of the arm being less than the distance between said axis and the first named horizontal support, a plurality of train order carrying members having shanks engageable with the extremity of each arm and projecting longitudinally therethrough when so engaged, and means on each arm engaging a serially successive arm to cause a rotation thereof when the first named arm has shifted from an approximately horizontal position toward a depending position.

13. A train order delivery mechanism including a frame, a supporting shaft mounted thereon, a horizontally disposed support mounted on the frame in advance of the shaft, a horizontally disposed support mounted on the frame above and rearward of the shaft, a plurality of arms unequally pivoted upon the shaft for movement in a vertical plane past said first named supporting means, said arms being adapted to be

- disposed in an upwardly and rearwardly inclined position against the second named supporting means, the shaft being independently rotatable with relation to the arms and
- 5 carrying an elongated link thereon engageable with the arms to rotate them unitarily, the shaft having means whereby it may be manually rotated, each of said arms having at one end means for detachable engagement with a train order carrying member, the distance between the axis of the arm and this end of the arm being less than the distance between said axis and the first named horizontal support, a plurality of train or-
10 der carrying members having shanks engageable with the extremity of each arm and projecting longitudinally therethrough when so engaged, and means on each arm engaging a serially successive arm to cause a rotation thereof when the first named arm
15 has shifted from an approximately horizontal position toward a depending position, said first named supporting member being pivotally adjustable upon the frame to raise or lower it, and adjustable braces engaging said supporting member and being formed to support signals.
14. A train order delivery mechanism including a series of independently rotatable, pivotally supported arms, each formed at one end with means for engaging a train order carrying member, means for supporting all of the arms in a raised position but permitting the rotation of the arms to a horizontal position, a horizontally disposed support upon which the train order carrying members may rest when the corresponding arm is in a horizontal position, and means operated when a train order carrying member is removed from any one arm with the arm in a horizontal position causing the rotation of the arm next adjacent in either direction to a horizontal position.
15. A mechanism of the character described including a plurality of order carrying arms shiftable from a retracted to a projected delivery position, and means causing the projected arm to automatically shift to a retracted position upon the removal of

an order from said arm and cause an arm next adjacent in either direction to be shifted from a retracted to a projected delivery position.

16. A train order delivery mechanism including a plurality of pivoted arms, each formed at one end with means for engaging a train order carrying member, means for supporting said arms in a retracted position but permitting the arms to swing to a delivery position, means for supporting any one of said arms in a delivery position with the corresponding train order carrying means projected, and means acting upon the removal of a train order carrying member from the last named arm causing a serially successive arm to swing from its retracted to its projected delivery position, and manually actuatable means for resetting all of said arms to their retracted position. 70

17. A train order delivery mechanism including a plurality of independently pivoted arms, each formed at one end with means for engaging a train order carrying member, a support for said arms supporting the arms in an upwardly and rearwardly inclined position, said support being adjustable to vary the inclination of the arms and said support permitting the arms to swing to a delivery position and then to a depending position, means for supporting any one of said arms in an approximately horizontal position, a support disposed in an approximately horizontal position and with which the train order carrying member on any one 85 of said arms is adapted to engage, said support being vertically adjustable to control the angle of said arms when in a projected position, and means acting upon the removal of a train order member from any 90 arm in a projected position, causing a serially successive arm to swing downward from its upwardly and rearwardly inclined position.

In testimony whereof I hereunto affix my signature in the presence of two witnesses.

GRANVILLE E. LUNTSFORD.
